UNITED STATES PATENT OFFICE

2,165,843

POCKET

Abraham Feit, Brooklyn, N. Y.

Application October 24, 1938, Serial No. 236,678

1 Claim. (Cl. 2-253)

In the patent granted to Hyman Feit, No. 1,734,422 dated November 5, 1929 there is disclosed a garment in which a secondary or safety pocket adjacent to the regular pocket of the garment is closed and opened by actuating a slider associated with a pair of tapes having interlocking fastening elements secured to a cloth wall intermediate the two pockets, the slider being accessible through the slotted opening at the side 10 of the garment which also gives access to the regular pocket. Owing to the fact that the slider and the metal parts of the tapes as shown in that patent are exposed on the intermediate wall it has been found that the said parts are harsh to the 15 hand when inserted in the regular pocket, and are not fully obscured from view in some wearing positions assumed by the cloth adjacent the slotted opening.

With the object of overcoming the foregoing 20 objections I provide a cover for the metal parts in the form of a strip of cloth fast to the main body portion of the garment and facing the opposite wall of the regular pocket, the strip or flap being readily movable by the inserted fingers to 25 permit operation of the slide, while at the same time providing a shield during ordinary insertion and withdrawal of the hand.

Various other objects and advantages of the 30 invention will appear as the description proceeds, reference being made to the accompanying drawing in which:

Figure 1 is a front view of the pocket portion with parts broken away of a pair of trousers incorporating my invention;

Figure 2 a cross section on the line 2-2 of Figure 1, and,

Figure 3 a fragmentary rear view of a pair of trousers illustrating the application of the invention to a rear pocket.

In the drawing which is merely exemplary of one practical form of the invention the reference numeral 10 indicates in general that section of a pair of trousers adjacent the front right-hand pocket. A regular or main pocket 11 and a secondary or safety pocket 12 are each adapted to be entered through the usual slotted opening 13 at the side of the garment, and form in effect a pocket within a pocket. This double pocket comprises a rear wall 14, an intermediate wall 15, and a front wall 16, all three of which are fastened together at a common point 17 forming one edge of the double pocket. The intermediate wall or partition 15 includes two sections 18 and 19 detachably secured together by tapes 20 and 21 having interlocking fastening elements 22 oper-

ated by a slider 23 in the usual well known manner for engaging and disengaging the elements. The rear wall 14 and the outer edge of the cloth section 19 are secured at 24 to the body portion 25 of the garment adjacent the opening 13. The 5 front wall 16 includes a facing piece 26 the outer edge of which is secured to the front cloth 27 at 28.

In order to shield the fastening elements 22 and the slider 23 there is provided a strip of material such as cloth 29 preferably fastened by rows of stitches at the points 30 and 31 to the intermediate wall 15 but unsecured at its top and bottom edges so as to form a free flap overlying the metal parts so that the hand may have free 10 access to the pocket 11 without contacting the fastening elements 22 or the slider 23, as will be readily seen from a consideration of Figure 2. Preferably the facing 26 is coextensive with the shield to provide cooperating shielding pieces for 15 the hand at opposite sides of the pocket opening.

When it is desired to have access to the secondary pocket 12, the flap 29 is easily movable by the fingers to the position approximating that indicated by the dot-and-dash lines in Figures 1 and 25 2, wherein the entire flap from top to bottom is folded over to the left of its normal covering position, and the slider 23 then moved downward from the Figure 1 position to disengage the fastener elements 22.

It will be noted also in the drawing that the fastening elements 22 of the partition 15 are located at a point well inward from the mouth 13 of the main pocket 11, providing a substantial margin of material between the fastening means 35 22 and the vertical line of stitches 30. This permits sufficient freedom to allow the element carrying portions of the partition 15 to expand or bulge away from the rear wall 14 when entering the hand into the safety pocket through the 40 opening provided by disengaging the fastening elements, thereby facilitating entry and withdrawal of the hand. The shield portion extending across the section 19 functions both as a reinforcement and a finishing piece for the inside 45 of the main pocket, while the flap portion provides a smooth lining over the fastening means and tends to prevent impressions of the latter from appearing in the outer cloth of the garment. Also, it will be seen from the drawing that the 50 vertical line of stitches 31 forming the hinge of the flap is located well inward from the mouth 13 of the main pocket 11, whereby the flap is at all times concealed within the confines of the main pocket, and that the flap is freely foldable 55

along its entire length to afford easy access to the fastening means.

Figure 3 illustrates the application of the invention to the rear pocket for instance of a garment in which the protective flap 29 extends cross-wise and may be lifted readily to give finger room for operating the slider 28.

The invention may be embodied in numerous other ways, and therefore is not limited in its applications except as set forth in the appended claim.

Having thus described my invention, I claim and desire to protect by Letters Patent:

A double pocket construction for a garment, comprising a main pocket and a safety pocket including front and rear walls and a partition separating the main pocket from the safety pocket, said partition having an opening, the edges of the material at opposite sides of said opening being provided with tapes having interlocking fastening elements adapted to be engaged and disengaged by operation of a slider, and a shield extending inward from the mouth of the main pocket and including a flap portion normally covering the fastening means and being foldable

to uncover said fastening means, said shield being connected to the garment by a vertical line of stitches adjacent the mouth of the main pocket and being also connected by a second vertical line of stitches to said partition forming a hinge connection for the flap at a point well inward from the mouth of the main pocket, whereby said flap is concealed whether folded toward the mouth of the main pocket or unfolded to cover the fastening means, said flap portion being free at its top and bottom edges affording foldability along its entire length to uncover the fastening means for operation, said fastening elements also being located well inward from the mouth of the main pocket providing a substantial width of partition material between the fastening elements and said first named vertical line of stitches, whereby the element carrying portion of the partition has freedom to bulge substantially away from the rear wall of the pocket and thereby provide for easy entry of the hand through the opening resulting from disengaging the fastening elements. 5 10 15 20 25

ABRAHAM FEIT. 25
